UNITED STATES PATENT OFFICE.

OSCAR H. HEINIG, OF CHICAGO, ILLINOIS.

MERCHANDISE-DISPLAY CABINET.

1,289,758.

Specification of Letters Patent. Patented Dec. 31, 1918.

Application filed January 5, 1918. Serial No. 210,471.

To all whom it may concern:

Be it known that I, OSCAR H. HEINIG, a citizen of the United States, residing at Chicago, in the county of Cook and State 5 of Illinois, have invented certain new and useful Improvements in Merchandise-Display Cabinets, of which the following is a specification.

The present invention has to do with certain improvements in merchandise display cabinets and the like, such as are used in merchandising of shirts, underwear, etc. While the features of invention are shown and described as used in connection with a 10 cabinet which is very well adapted for certain particular classes of service, still I wish to make it distinctly understood that the said features are in no wise limited to this particular or any other class of service. 15 One of the objects of the invention is to provide a cabinet which, when closed, will be to all intents and purposes dust-proof, and will fully protect the merchandise contained within it. Another object of the invention is to provide a display cabinet having a rack or drawer in which the merchandise may be carried, which rack or drawer may be slid out so as to expose the merchandise fully to the view of a customer, and 20 so as to facilitate the removal of the merchandise from the cabinet. Another object of the invention is to so relate such rack or drawer to the doors that as the rack or drawer is moved in and out the doors will 25 be automatically opened or closed as the case may be without particular attention on the part of the clerk.

Another feature of the invention has reference to the use of a concealed lock for 30 manipulating the movements of the drawer and doors, so that unauthorized persons will not readily gain access to the interior of the cabinet, and will not readily open the same.

Another feature of the invention has reference to the provision of an arrangement 35 such that it will be practically impossible for the clerk or other user to catch his hand or fingers between the doors as the drawer is closed, thus minimizing the possibility of accident in this regard.

Many other objects and uses of the invention will appear from a detailed description of the same which consists in the fea-

tures of construction and combinations of parts hereinafter described and claimed. 55

In the drawings:

Figure 1 shows a perspective view of a cabinet embodying the features of the present invention, the doors being fully opened, and the drawer or rack being partially withdrawn; 60

Fig. 2 shows a vertical cross section through the central portion of the structure, being a cross section substantially on the line 2—2 of Fig. 3, looking in the direction 65 of the arrows;

Fig. 3 shows a bottom plan view of the cabinet, the doors, drawer, and slide being in the fully closed position;

Fig. 4 shows a longitudinal section taken 70 on the line 4—4 of Fig. 3, looking in the direction of the arrows. Fig. 4 may also be considered as a section taken on the line 4—4 of Fig. 2, looking in the direction of the arrows; 75

Fig. 5 is a view similar to Fig. 4, with the exception that the slide has been withdrawn sufficiently to lock it to the drawer or rack;

Fig. 6 is a view similar to Fig. 5, with the exception that the slide has been still 80 further withdrawn so as to fully open the drawer or rack and the doors; and

Fig. 7 is a longitudinal section taken on the line 7—7 of Fig. 2, looking in the direction of the arrows, the drawer or rack 85 being fully opened.

As a matter of convenience in illustration, I have shown the features of the present invention as being applied to a self-contained cabinet which may be used either independently of other cabinets or which may be built into a stack of cabinets. The cabinet illustrated in the drawings comprises the box-like structure having the top 8, side walls 9 and 10, and back 11. Along the 90 bottom portions of the side walls 9 and 10 are secured the guide rails 12 and 13, and a cross piece 14 is secured across the bottom portion of the back 11. The blocks 15 and 16 are secured to the lower front portions of 100 the side walls 9 and 10 and to the front ends of the guide rails 12 and 13 respectively. Other rails 17 and 18 are secured between the inner ends of the blocks 15 and 16 and the back rail 14. This construction results 105 in the provision of three longitudinally ex-

tending slotted spaces, including the side spaces 19 and 20 and a central space, all as will be more clearly understood from an examination of the bottom plan view of Fig. 3.

5 Movable mounted within this box-like structure is the drawer or rack 21. The same has the bottom 22, side walls 23 and 24, and back 25. As a matter of convenience and neatness in design the front portions 10 of the side walls 23 and 24 are cut away or slanted down, as shown more particularly in Figs. 1, 2, and 6. This arrangement also facilitates in the handling of merchandise, such as shirts and the like, which may be 15 carried within the drawer.

Secured to the bottom portion of the drawer, are the extending guide rails 26 and 27. Each of these is provided with the side beads or tongues 28 and 29, best shown in 20 Fig. 2.

Mounted within suitable sockets or recesses of the rails 17 and 18 are the grooved rollers 30, 31, 32 and 33, the grooves of the rollers 30 and 31 engaging the tongue 28 of 25 the rail 26, and the grooves of the rollers 32 and 33 engaging the tongue 29 of the rail 27. By this arrangement the drawer may be very easily slid in and out with a roller bearing support.

30 A stop 34 secured to the front portion of the under face of the top 8 will limit the outward movement of the drawer by engaging with its back 25. Mounted within the central longitudinal space is a slide 35 35 which, in the construction illustrated, has a length substantially equal to the overall length of the cabinet. This slide carries the rollers 36, 37, 38, and 39 in its two side portions, the rollers 36 and 37 having grooves 40 engaging the tongue 29 of the rail 26, and the rollers 38 and 39 having grooves engaging the tongue 28 of the rail 27. Therefore, the slide has a roller bearing mounting. In its front portion the slide has a cross 45 piece or member 40 which is shown as having a greater width than the width of the slide itself, being in fact of a width sufficient to span the rails 26 and 27, as well as the slide itself, and being provided also with 50 a hand-hold 41, as shown in Figs. 1 and 3. Manifestly the slide 35 can be moved longitudinally with respect to the drawer 21, but it is nevertheless supported by the rails 26 and 27 on the drawer.

55 The parts are so proportioned that when the slide 35 is shoved back against the rails 26 and 27, and the drawer is fully closed into the position shown in Figs. 3 and 4, the cross piece 40 will stand substantially 60 flush with the front end of the cabinet. Upon locking the slide 35 in this position, the drawer will also be locked against pulling out because any forward movement of the drawer must be accompanied by a forward movement of the rails 26 and 27.

Means are provided for at times locking the slide 35 in its fully closed position of Figs. 3 and 4, and also for limiting the forward movement of the slide with respect to the drawer during the opening process so as to cause the drawer to travel forward with the slide at such time. For the latter purpose, the drawer is provided on its under portion with a slot or recess 42 within which works the upstanding arm 43 of a bracket 44, which bracket is secured to the top face of the slide 35. Since the arm 43 strikes the forward end of the slot 42 the drawer will be compelled to travel forward with the slide in the manner shown in Figs. 5 and 6. Nevertheless, on account of the presence of the slot 42, the slide 35 can be pulled out a distance substantially equal to the length of such slot before the movement of the drawer commences. In order to lock the slide in the fully closed position, its rear end is provided with a pawl 45 adapted to engage a pin 46 on the top face of the back bar 14, a spring 47 normally insuring such engagement. A rod 48 connects to said pawl and passes forwardly through a hole or channel 49 in the slide, the forward end of such rod carrying a finger piece 50 within the hand hold 41. Upon pulling such finger piece forward the pawl or hook 45 will be 95 disengaged from the pin 46 to permit the slide to be advanced. The slide will continue such advancement independently until the drawer is compelled to travel with it in the manner already explained.

100 The doors 51 and 52 are hinged to the front ends of the side walls 9 and 10 respectively. These doors close together above the slide 35 but in front of the lower or bottom portion 22 of the drawer. Therefore, as soon as the drawer begins to move out, the doors will be contacted and be swung open into the position shown in Fig. 1, so that they stand at right angles to the front of the cabinet, and parallel to its sides. In 110 order to facilitate this opening movement the side portions of the bottom 22 may be curved as shown in Fig. 1.

115 Means should be provided for closing the doors when the drawer is moved into its closed position, and I have provided means for automatically accomplishing this result. This means takes the form of the rods 53 and 54 working within the spaces 19 and 20 respectively and having their front 120 ends pivoted to the doors 51 and 52 at the points 55 and 56 respectively. The rear ends of these rods are connected to blocks 57 and 58 which are slidably mounted within the spaces 19 and 20, a simple form of 125 mounting being that shown in detail in Fig. 2. The stop lugs 59 and 60 mounted on the bottom of the drawer are so positioned that when the drawer is fully closed the blocks 57 and 58 are moved backwardly a sufficient 130

distance to fully close the doors and hold them in such condition.

In many cases it will not be necessary to provide any lost motion or free movement as between the slide 35 and the drawer. In fact, as far as the constructions so far described are concerned, such free movement is not necessary. In such case the front end of the slide and the hand-hold 41 will occupy a position in very close proximity to the space between the doors during the closing operation, since with such an arrangement the slide will be almost fully inserted as the doors come together. This might result in pinching or catching the hand or finger of the clerk in his haste on some occasions to close the cabinet, or a cloth or other article removed from the cabinet might become caught between the doors. By providing the lost motion previously referred to, the hand-hold 41 will occupy a projected position such as shown in Figs. 1, 5, and 6, even when the drawer is fully closed, provided that means be established for locking the slide temporarily to the drawer while the slide is in the projected position illustrated. Such means I have illustrated, the same comprising a pawl or finger 61 pivoted to the bracket 44 at the point 62 and adapted when in one position to seat in front of a pin 63 lying across the forward portion of the slot 42. A spring 64 tends to move the pawl 61 into such position. A finger 65 on the lower end of the pawl engages with a portion 66 of the rod 48, so that upon pulling the finger piece 50 forward, the pawl can be permitted to seat in front of the pin 63, and thereby lock the slide for the time being in the projected position with respect to the drawer. Thereupon by pushing back on the hand-hold 41, the drawer will be forced into closed position and the doors will swing together while the handhold is still projected such a distance in advance of the cabinet as to remove any possibility of accident. Thereafter the finger piece 50 may be pulled to disengage the pawl 61, after which the slide may be forced back and locked in its extreme closed position.

While I have herein shown and described only a single embodiment of the features of my invention, still it will be understood that I do not limit myself to said embodiment, except as I may do so in the claims.

I claim:

1. In a device of the class described, the combination with a casing having its front end open, and a pair of doors therefor, of a drawer slidably mounted within the casing and working through said open end, and adapted to swing the doors into open position when it is advanced, a slide bar longitudinally movable with respect to the drawer through a predetermined amount of

lost motion, means for compelling the drawer to travel forwardly with the slide when said lost motion has been taken up, means for preventing the drawer from moving forwardly with respect to said slide 70 when at the other limit of such lost motion, means for locking the slide to the casing when the slide and drawer are in their fully closed position, and the slide stands at its back limit of lost motion with respect to the drawer to thereby lock the drawer in closed position, means for locking the slide to the drawer when the slide has been advanced to its limit of movement of lost motion, a hand-hold on the front end of the slide, and 80 means adjacent to said hand-hold and under the control of the operator for disengaging both of said locking means at the will of the operator, and means whereby the drawer closes the doors, as the drawer is moved into 85 its closed position, substantially as described.

2. In a device of the class described, the combination with a suitable casing having a front opening, of a drawer slidably mounted 90 with respect to the casing and working through said opening, doors for the opening, a slide mounted on the drawer, and having a predetermined amount of lost motion with respect thereto, a hand-hold on the 95 front end of the slide, means for limiting the movement of the slide in either direction with respect to the drawer, means for at times locking the slide at the extreme forward limit of its lost motion with respect to 100 the drawer, means for at times locking the slide to the casing when the slide is at its back limit of lost motion with respect to the drawer and the drawer is in fully closed position, means adjacent to the hand-hold and 105 under the control of the operator for disengaging said locking means, and means whereby the drawer closes the doors, as the drawer is moved into its fully closed position, substantially as described. 110

3. In a device of the class described, the combination with a suitable casing having an opening in its front end, of a drawer working through said opening, a closure for said opening, a slide mounted on the drawer 115 and having lost motion with respect thereto, means for limiting the amount of such lost motion in either the forward or backward direction, means for locking the slide to the drawer at the forward limit of lost 120 motion, and means for locking the slide to the casing when the slide is at the back limit of the lost motion and the drawer is in fully closed position, means under the control of the operator for disengaging said locking 125 means, and means whereby the drawer closes the closure, as the drawer is fully restored to its closed position, substantially as described.

4. In a device of the class described, the combination with a suitable casing having 130

4
an opening, of a drawer working through such opening, a closure for the opening, a slide mounted on the drawer, means for locking the slide to the casing when the drawer and slide are in fully closed position, means under the control of the operator for disengaging said locking means, and means whereby the drawer closes the closure, when the drawer is in fully closed position, substantially as described.

5. In a device of the class described, the combination with a suitable casing, of a drawer slidably mounted thereon, a closure on the casing working in front of the drawer when the same is closed, an interconnection between the drawer and the closure for closing the closure when the drawer is restored to closed position, a hand-hold, a slidable

connection from the hand-hold to the drawer permitting a predetermined amount of lost motion between these parts, and means for at times locking the hand-hold to the drawer in advanced position for the purpose specified.

6. In a device of the class described, the combination with a suitable casing, of a drawer working therein, a closure working in advance of the drawer, an interconnection between the drawer and closure for closing the closure when the drawer is restored to fully closed position, a hand-hold, a movable connection between the hand-hold and the drawer, and means for locking the hand-hold in moved position with respect to the drawer for the purpose specified.

OSCAR H. HEINIG.
